UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

DRAFT RIGGING BACKSTOP

Application filed October 22, 1928. Serial No. 314,186.

This invention relates to draft rigging and more particularly to a backstop adapted to tie together the associated center sills and receive buffing forces from an associated yoke.

5 The principal object of my invention, generally considered, is to provide a backstop for round ended yokes with the front wall correspondingly curved and reinforced by a hollow wall preferably oval in cross-section 10 extending rearwardly from said front wall to a transverse wall connecting intermediate portions of the side walls.

Another object of my invention is to provide a combined backstop and center filler 15 casting with the front face concavely curved for engagement with a round ended yoke and reinforced by a longitudinally disposed hollow spool elliptical in section extending from the front wall to a transverse wall in which 20 is formed the king pin aperture, the lower edge of said intermediate wall being provided with a transverse wall connecting the lower edges of the side walls and adapted for engagement with an associated center plate.

25 A further object of my invention is to improve the construction of backstop castings by reducing the rear overhang, cutting off the top corners of the side walls to avoid bending in shipment and at the same time have a larger 30 percentage of the total number of connecting rivets substantially symmetrical with respect to the center line of draft.

Other objects and advantages of the invention relating to the particular arrangement and construction of the various parts 35 will become apparent as the description proceeds.

Referring to the drawing illustrating my invention, the scope whereof is defined by the 40 appended claims.

Figure 1 is a plan of a backstop casting embodying my invention, a portion thereof being illustrated in horizontal section and a portion of an associated yoke being diagrammatically indicated.

Figure 2 is a longitudinal vertical sectional view on the line 2—2 of Figure 1, looking in the direction of the arrows.

Figure 3 is a partial end elevational and 50 partial transverse sectional view on the line

3—3 of Figure 1, looking in the direction of the arrows.

Figure 4 is a transverse vertical sectional view on the line 4—4 of Figure 1, looking in the direction of the arrows.

Referring to the drawing in detail, like parts being designated by like reference characters, I have shown a draft rigging backstop casting 1 which preferably also functions as a center filler casting and is provided with side walls 2 adapted for connection with associated center or draft sills (not shown) and a front wall 3 preferably concavely curved on its front face to receive a round ended yoke diagrammatically indicated at 4 and adequately reinforced as more fully described hereinafter for receiving buffing forces therefrom.

Intermediate portions of the side walls 2 and the front wall 3 and preferably connected by a pair of diagonally extending vertical walls 5, which walls are also preferably approximately radial with respect to the curvature of the front wall 3. The front wall 3 forwardly or outwardly of said connecting 45 and reinforcing walls 5 is preferably indented as indicated at 6, and the corresponding portions of the side walls 2 are apertured at 7 for receiving connecting rivets (not shown).

The front wall 3 is preferably additionally reinforced by means of a longitudinally extending center spool or tubular web 8 which connects with a transverse wall 9 extending between intermediate portions of the side walls 2 and preferably expanded at its 50 central portion to provide a vertical aperture 10 for receiving an associated king pin (not shown). The major axis of the oval or elliptical section of the reinforcing web 8 is preferably horizontal and the side edges of 55 said reinforcement are connected with the side walls 2 by horizontal webs 11 as most clearly shown in Figures 1 and 4. For still further reinforcing the front wall 3, longitudinally disposed preferably triangular 60 gussets 12 are preferably provided above the reinforcing web 8 thereby bracing the upper extension or flanged portion 13 of the front wall above the reinforcing web 8. The purpose of this extension is to raise the center of 65

106

the front wall 3 to correspond with the center line of draft which is above that of the elliptical reinforcement 8. In order to provide for core removal, the front wall 3 is preferably apertured as indicated at 14 to give access to the interior of the reinforcing web 8 and the hollow in said web is also joined with the king pin aperture 10 as shown most clearly in Figures 1 and 2.

- 10 The transverse web 9 is preferably increased in depth upwardly toward the side walls 2 as indicated at 15 to properly reinforce said walls, and the lower edge is connected to a transverse web 16 connecting the 15 lower edges of the walls 2. Said web 16 is preferably horizontal adjacent the center and upwardly indented adjacent the side walls as indicated at 17 for receiving the lower flanges of the associated center sills 20 (not shown). The web 16 is of sufficient width to provide the necessary bearing area for the associated center plate (not shown). The web 16 is desirably reinforced by longitudinal preferably centrally disposed triangular webs or gussets 18 and 19, the former of which merges into the hollow post with the king pin aperture 10 and the latter of which connects with the oval reinforcement 8.
- 30 Although the oval reinforcing web 8 is preferably not continued rearwardly of the transverse web 9, that portion of the casting is preferably provided with a transverse curved web 20, the central portion of which 35 corresponds in elevation with the top of the reinforcement 8 and the sides of which correspond with the connecting webs 11 so that the web 20 is preferably convex upwardly adjacent the longitudinal center line to correspond with the corresponding portion of the reinforcement 8 and on either side thereof concave upwardly to smoothly merge into horizontal portions 21 corresponding in elevation with the webs 11 and connecting with 40 the side walls 2 of the casting. The rear edge of the web 20 is preferably reinforced by a transverse vertical web or flange 22, the top edge of which is preferably flush with the top of the curved web 20 and the bottom 45 edge of which preferably corresponds with the bottom of the horizontal side portions 21. The side webs or walls 2 are preferably continued rearwardly beyond the rear wall or web 22 to provide sufficient riveting area 50 and are reinforced with respect to said wall by triangular webs or gussets 23. In order to avoid bending during shipment, the top corners of the side walls 2 are desirably cut off as indicated at 24 and 25, and the lower 55 corners rounded as indicated at 26 and 27.

From the foregoing disclosure, it will be seen that I have devised an improved backstop for a round ended yoke in which the correspondingly curved front wall is adequately reinforced by an elliptical center

spool spanning the critical area of the casting. The casting is of minimum weight consistent with strength on account of a reduction of the rear overhang and the removal of the top corners of the side walls, which at the same time avoids bending thereof in shipment. As an additional result, a larger percentage of the total number of connecting rivets, the apertures for which are indicated generally by the reference character 28, are arranged substantially symmetrical with respect to the center line of draft which is above that of the elliptical reinforcement for the front wall.

Having now described my invention, I claim:

1. A backstop casting comprising side walls adapted for connection with associated center sills, a front wall concavely curved horizontally on its front face and adapted to receive buffing forces from the correspondingly curved end of an associated yoke, forwardly and inwardly converging webs connecting intermediate portions of said side walls and front wall, said wall portions forwardly of said webs being apertured for receiving connecting rivets.

2. A backstop casting comprising side walls adapted for connection with associated center sills, a front wall adapted to be engaged by an associated yoke, a transverse wall intermediate the ends of said casting with the central portion thereof expanded into a hollow vertical post providing a king pin opening, and reinforcing means extending between said front and transverse walls, and formed as a hollow web substantially elliptical in section, the hollow in said web joining the king pin opening and a transverse floor portion connecting the lower edges of said side walls and extending beneath the hollow post and adjacent portion of the reinforcement.

3. A backstop casting comprising side walls adapted for connection with associated center sills, a front wall adapted to engage an associated yoke, a transverse reinforcing web disposed rearwardly of said front wall and uniting with said side walls between the upper and lower edges thereof, said web being convex upwardly adjacent the longitudinal center line and concave upwardly on either side thereof until it merges with the side walls of the casting, and a connecting transverse vertical web extending along the rear edge of said reinforcing web and disposed beneath said web adjacent the longitudinal center line of the casting and above said web adjacent the side walls.

4. A backstop casting comprising side walls adapted for connection with associated center sills, a front wall with its front face concavely curved and adapted to receive buffing forces from the correspondingly formed end of an associated yoke, the curved front

wall extending forward to meet the forward portions of the side walls and both apertured adjacent the junctions to receive rivets for connection with associated sills, longitudinal reinforcing means for said front wall comprising a hollow web oval in section extending rearwardly therefrom, the longitudinal center line of said web being slightly below the longitudinal center line of the associated yoke, and a transverse web connecting the side walls and merging with the reinforcing means.

5. A backstop casting comprising side walls adapted for connection with associated sills, a front wall horizontally curved and adapted to receive buffing forces from a correspondingly curved end of an associated yoke, said side walls having their upper edges sloping upwardly from the front wall and 10 sloping downwardly adjacent the rear portions thereof to avoid sharp corners, a tubular web extending rearwardly from the front wall and formed of a greater horizontal than 15 vertical dimension to span the critical area 20 of and reinforce said front wall, said side walls meeting the curved front wall forwardly 25 of the junction with the reinforcing web and apertured forwardly of said web for connecting rivets, a transverse vertical web reinforced by a horizontal rearwardly extending 30 web joining the side walls of the casting intermediate the ends thereof, the central portion of said web being formed hollow to provide 35 a king pin opening, the cavity in the tubular reinforcing web joining the king pin opening, and a transverse floor portion connecting the lower edges of said side walls and joined to the transverse and tubular reinforcing webs.

40 In testimony whereof I affix my signature.
DONALD S. BARROWS.
